US0D1046740S

(12) **United States Design Patent** (10) **Patent No.:** **US D1,046,740 S**
(45) **Date of Patent:** **** Oct. 15, 2024**

(54) **VEHICLE WHEEL**

(71) Applicant: **GM GLOBAL TECHNOLOGY OPERATIONS LLC**, Detroit, MI (US)

(72) Inventor: **Ryan D. Skelley**, Berkley, MI (US)

(73) Assignee: **GM GLOBAL TECHNOLOGY OPERATIONS LLC**, Detroit, MI (US)

(**) Term: **15 Years**

(21) Appl. No.: **29/882,357**

(22) Filed: **Jan. 13, 2023**

(51) LOC (14) Cl. **12-16**

(52) U.S. Cl.

USPC **D12/211**
